CHARGE FORMING DEVICE

Olin J. Eickmann, Normandy, Mo., assignor to
 Carter Carburetor Corporation, St. Louis, Mo.,
 a corporation of Delaware

Application October 2, 1950, Serial No. 187,887

29 Claims. (Cl. 261—39)

1

This invention relates to fuel mixing devices for internal combustion engines of the spray carburetor type, and particularly to such carburetors which may be required to handle gasolines which may contain a large proportion of low temperature boiling constituents.

The increasing use of highly volatile fuels has presented serious problems on account of the tendency of the fuel to boil and cause vapor lock and disturbance of the mixture ratios when the temperatures are high, and also to cause icing at lower temperatures.

Another serious problem presented by carburetors of previous design has been their inability to produce homogeneous mixtures and even distribution, particularly during variation of throttle position and changes in engine speeds.

Some previous attempts to avoid icing and poor fuel distribution by placing the throttle anterior to the fuel nozzle have been made, but these attempts have not been successful, chiefly by reason of the tendency to cause violent boiling of the fuel in the float chamber and nozzles whenever the throttle is closed.

Certain subject matter shown in this application is claimed in my copending application Serial No. 164,544, filed May 26, 1950, for "Carburetor and Method of Carburetion," now abandoned.

It is an object of my invention to produce a new and generally improved form of carburetor, in which the throttle is placed anterior to the fuel nozzle so as to obtain the advantages of the anterior throttle design without encountering the disadvantages caused by placing the fuel supply chamber and fuel nozzles under manifold suction when the throttle is in closed or idling position. It is a further object of this invention to produce a carburetor of the above described character in which the richness of the fuel mixture is controlled in accordance with temperature during the starting and warm-up period.

The problem of forming homogeneous fuel mixtures having the correct air-fuel ratio is sharply accentuated when the throttle is moved from closed to open position, or vice-versa. It is well known that the engine requires a much richer mixture from the carburetor when the throttle is in its idling position than when the throttle is open. This is partly because the volume of fresh mixture to be delivered to the engine during idling is much smaller in proportion to the volume of dead mixture remaining in the cylinder. As the volume supplied to the engine is increased, the proportion of fresh mixture to burnt gas is increased and therefore the richness

2

of the fresh mixture must be correspondingly reduced. In conventional plain tube carburetor practice, this reduction of richness has been accomplished by having the idle port in the wall of the carburetor adjacent one edge of the butterfly throttle valve so that the action of the port is varied during the opening movement of the throttle. With a construction of this type, the idle port ceases to discharge fuel when the throttle is about $\frac{1}{3}$ or $\frac{1}{2}$ way open and the fuel discharge function is then taken over by the main nozzle which discharges into the center of the mixing conduit at a point anterior to the throttle and usually near the throat of a venturi.

15 Carburetors of the type just described are in almost universal use for automobile engines, at present, but they present the serious disadvantage of being very hard to control at the point where the function of fuel supply is transferred from

20 the idle port to the main nozzle, or vice-versa. Carburetor engineers have probably spent more time in attempts to "cover up the transfer point" than in any other phase of carburetion.

It is an object of this invention to provide a 25 new and improved plain tube carburetor in which there is no transfer point and in which the function of discharging fuel is customarily performed from idling to wide open throttle by a single fuel supply system.

30 Another object is to provide novel means and method for supplying a temporary increase in the supply of fuel to the engine intake during acceleration.

These objects and other more detailed objects 35 hereafter appearing are attained by the structure illustrated in the accompanying drawings in which:

Figure 1 is an elevation showing the novel carburetor mounted on an engine manifold.

40 Figure 2 is a top view of the carburetor considerably enlarged.

Figure 3 is a vertical section on line 3—3 of Figure 2.

Figure 4 is a horizontal section on line 4—4 of Figure 3.

45 Figure 5 is a horizontal section on line 5—5 of Figure 3.

Figure 6 is an enlarged fragmentary view of the ports adjacent the throttle valve.

50 Figure 7 is a section similar to Figure 3, but showing a modification, like parts, in most cases, having the same reference numerals with the letter "a" added.

Figure 8 is a section similar to Figures 3 and 4, 55 but showing another modification, like parts, in

most cases, having the same reference numerals with the letter "b" added.

Figure 1 shows the carburetor, generally indicated at 10, attached to the hot spot portion 11 of an engine manifold system including the intake manifold, shown in part at 12, and the exhaust manifold at 13. The carburetor has a housing 14 enclosing a thermostatic control to be described hereafter and connected by a tube 15 to a stove 16 mounted on the exhaust manifold for supplying hot air.

The carburetor comprises a downdraft mixture conduit including an upper air inlet portion 18, which may be arranged for mounting of an air cleaner, a series of Venturi tubes 19 and a discharge portion 20 flanged as at 21 for attachment to the manifold. Adjacent the mixture conduit is a bowl 22, having a threaded boss 23 for connection to a source of fuel, within which fuel is maintained at a substantially constant level by a float 24 and the usual needle valve mechanism (not shown). A main fuel passage 25 extends from the lower part of the fuel bowl upwardly at an angle and discharges through a main fuel nozzle 26 into smallest Venturi tube 19. A metering restriction for the main fuel supply is shown at 27.

A butterfly throttle valve 28 is mounted in the air inlet portion of the carburetor on a shaft 30 which rigidly mounts a manual operating lever 31 outside the carburetor. Lever 31 carries an idle speed adjusting screw 32 which cooperates with a stop 33 on the carburetor mixture barrel.

The fuel bowl is sealed from the atmosphere, except through a bowl pressure control duct 34 leading transversely from the top of the bowl to a vertical passage 35 on the opposite side of the mixture conduit. Passage 35, at its lower end, has a restriction 36 and opens into the mixture conduit through a cross port 36 controlled by a plug or drum type enriching valve 37 to be described hereafter. At its upper end, passage 35 connects with the mixture conduit anterior to throttle 29 through an upwardly inclined cross tube 39 containing a restriction controlled by a needle valve 41. The mouth of cross tube 39 is cut at an angle of about 45° to the vertical so as to face against the direction of air flow in the mixture conduit. The upward inclination of tube 39 tends to prevent collection of condensed vapors therein.

A main air bleed duct consisting of passages 42 and 44, containing restriction 45, leads from main fuel passage 25 to tube 46 located anterior to the throttle valve. Passage 42 is in communication with air inlet portion 18 through port 43 located immediately anterior to throttle valve 29 when the throttle valve is in closed position. The position of this port is such that it is swept by the edge of the throttle valve during the early part of the throttle opening movement from dead idle and thereafter part or all of port 43 is exposed to engine suction for the purpose of reducing the value of the air bleed to nozzle 25 which in turn increases fuel discharge from said nozzle. The main air bleed passage also communicates with the main nozzle passage through branch passage 47 for calibrating purposes. This latter passage 47, however, is optional. The intersections of bleed 42 and diagonal passage 47 with main fuel passage 25 are both normally below the normal fuel level and constitute metering points which may be proportioned as required. Inlet 18 of the carburetor will be at substantially atmospheric pressure during normal operation.

The angles of the open ends of tubes 46 and 39 are subject to variations to adjust the mixture proportions required under various operating conditions.

5 In order to further limit the bad effects of percolation, main nozzle 26, above restriction 27, is of ample diameter to permit breakage of independent bubbles from the surface of the fuel.

10 Drum valve 37 provides for adjusting the pressure in bowl 22, and consequently, enriching the fuel discharge during starting and warm-up and also provides for a fast idle. This valve extends into housing 14, previously mentioned, which has a cover 14a with a central pin 49 to which is

15 secured the inner end of a coiled thermostatic spring 50. A threaded boss 51 provides for connection of heat tube 15 to the thermostat casing. The outer end of the thermostat is connected by a loop 50a to a finger 52 on the outer extremity of a lever 53 rigid with drum valve 37. The arrangement is such that at low temperatures, thermostat 50 unwinds and rotates drum valve 37 counterclockwise, as viewed from the left side of Figure 3. This valve has a V-shaped, peripheral slot 55, in line with vertical passage 35 forming part of the bowl pressure control system, and also has a port 56 spaced therefrom. Port 56, during rotation of valve 37, moves along the edge of curved, inclined wall 57, for exposing more or less of the port to the interior of the thermostat housing. Slot 55 and port 56 both communicate with cross passage 36 and the interior of the mixture conduit through the hollow interior of the drum valve.

35 The arrangement of slot 55 and port 56 is such that at low temperatures, as shown in Figure 7 (in which the drum valve is identical) the communication between passages 36a and 35a (36 and 35 in Fig. 3) through slot 55 is substantially restricted.

40 The effect of this is that the pressure in the top of the fuel bowl is higher than is the case when the bowl pressure control system opens to a greater extent through cross port 36a into the mixture conduit. This results in increased discharge of fuel for starting and warm-up. At such time, port 56 is substantially opened to the interior of the thermostat housing and stove 16 so that the increased flow of air from heat tube 15 through port 36a provides fast idle operation.

45 As the thermostat becomes warm, due to the flow of heated air through tube 15, it winds upon itself to rotate drum valve 37 clockwise, as viewed from the left side of Figure 7, progressively cutting off communication between port 36a and the inside of the thermostat housing through port 56, while increasing the communication between port 36a and the bowl pressure control system so as to, in effect, reduce the pressure on the fuel in the constant level bowl. Figure 8 shows the

50 starting valve in a warm-up position with port 56 and slot 55b each only partially opened, respectively, to the interior of the thermostat housing and to bowl pressure passage 34b. During the warm-up, the communication between heat tube 15 and the mixture conduit gradually decreases so that the supplemental feed of warm air to the mixture conduit and, consequently, the idle speed are gradually reduced.

55 After starting, the bowl pressure control system, including the throttle, and tube 39 opening into the conduit anterior to the throttle, cooperate with the air bleed system, including port 43, just anterior to the edge of the throttle when closed, passages 44 and tube 46, somewhat farther anterior to the throttle, to provide a

properly metered and modulated fuel flow in accordance with all speed and load conditions. The carburetor operates economically, yet has adequate power under severe testing conditions, even without the usual accelerating pump, step-up, and separate idling system. After starting valve 37 has reached its normal position of Figure 3, fuel modulation is obtained without any valve or other moving part, except the throttle valve, simply by control of pressures in the fuel bowl and in the air bleed system. At normal engine temperature, only slight communication is provided through port 56 between the mixture conduit and heat tube 15 to insure maintenance of the starting valve 37 in normal running position.

The functioning of the carburetor under acceleration and load conditions is novel and advantageous. In conventional posterior throttle carburetors, it has been necessary to supplement the fuel supply at such times by the use of an accelerating pump and step-up devices. Since the pressure on top of the fuel in the constant level chamber in my carburetor varies in accordance with the induction system pressure applied to port 36, of course, as moderated by air tube 39, and restriction 38, there will be a sharp increase of bowl pressure when the throttle is opened or the load on the engine increased. Simultaneously, the amount of air bled through the nozzle via passage 42 and 47 is greatly reduced due to the reduction of the pressure differential between the nozzle tip at 26 and tube 46. Those two factors cause a surge of fuel through the main nozzle and consequent added enrichment. The added enrichment continues until the induction pressure again drops to normal so that a "step-up" or "economizer" effect is obtained without the use of a metering valve or supplemental feed. It will be noted that as the throttle valve is moved to nearly fully open position, the anterior edge of the valve 29 approaches the mouth of the tube 46b, so that the incoming air stream is directed toward the mouth of the tube as by a vane, thus causing the air to enter the tube and increase the pressure above the fuel in the bowl 22. By this means, the rate of flow of fuel from the bowl out of the nozzle 26 is increased when the throttle is moved to fully open position. Also, to be considered a factor in acceleration is the fact that when the edge of the throttle passes beyond port 43, the diluting effect of air in the bleed passage is further reduced.

The positioning of the main nozzle posterior to the throttle insures the exposure of the fuel discharge to the maximum suction available in the induction system while, at no time during engine operation, will there be a failure of suction at this point. The result is that vaporization is improved and a supply of fuel is maintained in the main nozzle at all times. In previous carburetors, particularly, of the interconnected idle type, there has been a time interval required in transferring the fuel feed from the idle system to the main nozzle. This time delay is avoided in my carburetor. Furthermore, the interference of the throttle with the free and direct flow of fuel, as present in posterior throttle carburetors, is also avoided.

The control of the pressure on the fuel in the bowl, plus the variable air bleed through the nozzle, in accordance with induction pressure, as above described, has a further important advantage in that a rich or power mixture may

be obtained for any throttle position upon drop of manifold suction. This advantage, heretofore, has required a separate vacuum step-up device with resultant increased cost and liability to malfunctioning. In my carburetor, an increase of pressure, or decrease of suction, in the manifold, as when the engine is subjected to increased load, is promptly transmitted to the body of gaseous fluid in the top of the fuel bowl and to the nozzle bleed system. The proportionate increase in bowl pressure under such condition is greater than the increase in pressure at the mouth of main nozzle 26 due, in part, to the effect of primary Venturi tube 19 and the location of suction port 36 outside the Venturi stack. Also, there is less air bled through the nozzle. The net result is a desirable enrichment of the fuel mixture without movement of the throttle valve 29. This new method of providing for mixture variation in accordance with the requirements of economy, power, acceleration, and starting operation, particularly, with the use of a constant level bowl and without valves and metering pins, pistons, diaphragms, springs, etc., is an important feature of the invention, accounting for improved operation and greater simplicity and economy.

The form in Figure 7 differs from that in Figure 3 in that the bowl pressure control system, including vertical passage 35a opens into the mixture conduit through a port 60, immediately posterior to the edge of the throttle valve when closed, and an upwardly inclined cross tube 39a containing a restriction controlled by needle valve 41a. In this form, as previously explained, enriching valve 37 is shown in its cold starting position. In this construction, port 60 cooperates with port 43a to shape the inner end of the part throttle curve, that is the mixture delivery as the throttle starts to open from dead idle.

The form in Figure 8 differs from the previous form in that the air bleed system opens into the mixture conduit only through tube 46b, port 43a of Figure 7 being omitted. The bowl pressure control system is the same as in Figure 7, including passage 34b and 35b, port 60b, inclined tube 39b, and needle valve 41b. The enriching valve 37, in this form, is shown in the warm-up position, with the bowl pressure control system partially open to the mixture conduit through cross passage 36b and partially open to the interior of the thermostat housing and heat tube 15. This latter connection insures the drawing of hot air past the thermostat from the stove.

The various bleed and pressure controlling passages, with their accompanying restrictions, may be modified as required to obtain the necessary fuel mixture, as determined by well known test procedures. For instance, the angle of impact tube 39 and air bleed tube 46 may be varied, as may the positioning and sizes of ports 43 and 60. The exclusive use of all modifications as come within the scope of the appended claims is contemplated.

I claim:

1. In a carburetor, a mixture conduit, a throttle valve therein, a constant level fuel bowl, a main fuel passage leading from said bowl and discharging into said conduit posterior to said valve, and a bowl pressure control duct leading from the upper part of said constant level bowl 75 to said conduit posterior to said throttle said

pressure control duct having a branch to a point in said conduit anterior to said throttle.

2. In a carburetor, a mixture conduit, a throttle valve therein, a fuel bowl, a main fuel nozzle connecting said bowl and said conduit posterior to said valve, and bowl pressure control passages extending, respectively, from a zone of substantially atmospheric pressure and from said conduit posterior to said throttle valve to the upper portion of said bowl for applying to the fuel in said bowl the resultant of pressures in said passages.

3. In a carburetor, a mixture conduit, a throttle valve therein, a constant level fuel bowl adjacent said conduit, a main fuel nozzle extending from the lower part of said bowl into said conduit posterior to said valve, and bowl pressure control passages extending, respectively, from a zone of substantially atmospheric pressure and from said conduit posterior to said throttle valve to the upper portion of said bowl for applying to the fuel in said bowl the resultant of pressures in said passages.

4. On a carburetor, a mixture conduit, a throttle valve therein, a constant level fuel bowl, a main fuel passage extending from said bowl to said conduit posterior to said throttle valve, a fuel control means comprising an air bleed duct extending from said fuel passage to a port in the wall of said conduit immediately anterior to the edge of said throttle valve when closed, and bowl pressure control passage means extending from the upper portion of said fuel bowl into said mixture conduit on opposite sides of said throttle valve, when closed.

5. In a carburetor, a mixture conduit, a throttle valve therein, a constant level fuel bowl, a main fuel passage extending from said bowl to said conduit posterior to said throttle valve, and fuel control means comprising an air bleed duct extending from said fuel passage to said mixture conduit anterior to said valve, a valve swept port in said duct, and bowl pressure control passage extending from the upper portion of said fuel bowl into said mixture conduit on opposite sides of said throttle valve when closed.

6. In a carburetor, a mixture conduit, a throttle valve therein, a constant level fuel bowl, a main fuel passage extending from said bowl to said conduit posterior to said throttle valve, and fuel control means consisting of an air bleed duct leading from said fuel passage below the normal level of fuel therein to said mixture conduit anterior to said throttle valve, and a bowl pressure control passage extending from the upper part of said bowl and having branches opening into said conduit on opposite sides of said valve.

7. In a carburetor, a mixture conduit, a throttle valve therein, a constant level fuel bowl, a main fuel passage extending from said bowl to said conduit posterior to said throttle valve, and fuel control means consisting of bowl pressure control passages extending, respectively, from a zone of substantially atmospheric pressure and from said conduit posterior to said throttle valve to the upper portion of said bowl, and an air bleed duct leading from said main fuel passage to said mixture conduit anterior to said throttle, with a branch passage extending from said air bleed duct to a valve swept port in the wall of said mixture conduit immediately anterior to the valve for controlling the fuel discharge from said passage.

8. A carburetor as described in claim 6 in

which the bowl pressure control passage opening into said conduit anterior to said throttle faces against the air flow in said conduit.

9. A carburetor as described in claim 6 further including an adjusting valve in said control passage.

10. A carburetor as described in claim 6 in which the bowl pressure control passage opening into said conduit anterior to said throttle has a plurality of connections with said conduit, and a manually adjustable needle valve in one of said connections.

11. In a carburetor, a mixture conduit, a throttle valve therein, a constant level bowl, a main fuel passage connecting said bowl and said conduit posterior to said throttle valve, a bowl pressure control duct extending from the upper part of said bowl to said mixture conduit for controlling the fuel discharge from said passage and a thermo-responsive enriching valve in said duct functioning to increase the pressure therein and in said bowl for increasing the fuel discharge during starting and warm-up.

12. In a carburetor, a mixture conduit, a throttle valve therein, a constant level bowl, a main fuel passage connecting said bowl and said conduit posterior to said throttle valve, a bowl pressure control duct extending from the upper part of said bowl to said mixture conduit for controlling the fuel discharge from said passage, a connection between said duct and a zone of atmospheric pressure, and thermo-responsive valve means controlling said duct and said connection and actuatable to open said duct to said zone during starting and warm-up for increasing the pressure in and the fuel discharge from said bowl into said conduit.

13. A carburetor as described in claim 12 in which said enriching valve includes portions for reducing the effective size of the connection between said bowl pressure control duct and said conduit, while increasing the effective size of the connection between said conduit and said zone of atmospheric pressure.

14. In a carburetor, a mixture conduit, a throttle valve therein, a constant level fuel bowl, a main fuel passage extending from said bowl to said conduit posterior to said throttle valve, and fuel control means comprising an air bleed duct extending from said fuel passage to a port in the wall of said conduit immediately anterior to said throttle valve when closed and a bowl pressure control duct extending from the upper part of said bowl and having branches terminating in said conduit on opposite sides of said valve.

15. In a carburetor, a mixture conduit, a throttle valve therein, a constant level fuel bowl, a main fuel passage extending from said bowl to said conduit posterior to said throttle valve, and fuel control means comprising an air bleed duct extending from said fuel passage to a port in the wall of said conduit immediately anterior to said throttle valve when closed and a bowl pressure control duct extending from the upper part of said bowl and having branches terminating in said conduit through ports located, respectively, anterior and immediately posterior to said throttle valve.

16. In a carburetor, a mixture conduit, a throttle valve therein, a constant level fuel bowl, a main fuel passage extending from said bowl to said conduit posterior to said throttle valve, and fuel control means comprising an air bleed duct extending from said fuel passage to said

conduit immediately adjacent to the edge of said valve when closed and a bowl pressure control duct leading from the upper part of said bowl to a pair of ports in the wall of said conduit, respectively, immediately posterior to said throttle valve when closed and at a substantially greater distance posterior to said valve.

17. In a carburetor, a mixture conduit, a throttle valve therein, a constant level fuel bowl, a main fuel passage extending from said bowl to said conduit posterior to said throttle valve, and fuel control means comprising an air bleed duct extending from said fuel passage to a pair of ports in the wall of said conduit, respectively, immediately anterior to said valve and at a greater distance anterior thereto and a bowl pressure control duct leading from the upper part of said bowl to said conduit both anterior and posterior to said valve.

18. In a charge forming device for internal combustion engines, walls forming an intake conduit, said intake conduit having an air inlet, a mixing chamber, and a discharge outlet, a fuel bowl for said charge forming device, means comprising a fuel supply conduit for maintaining the fuel level in said supply chamber, a main fuel passage leading from a point below the fuel level in said fuel bowl and having an outlet in the intake conduit, a throttle valve at a position in said intake conduit anterior to said fuel passage outlet, an air passage leading from a point in said intake passage anterior to the closed position of said throttle to said fuel passage outlet, said throttle being of the butterfly type and being so arranged and positioned with respect to the air passage that the portion of the periphery of the valve nearest the opening of the air passage moves toward the air inlet of the intake conduit during the opening movement of the throttle, and in such proximity to the air passage opening as to permit suction posterior to the throttle to affect and reduce the pressure at the said air passage opening, and a second air passage leading from a point in said air passage anterior to the closed position of said throttle to said fuel passage outlet, said second air passage having an inlet in such proximity to said throttle valve when it is moved to fully open position as to cause the pressure at the said inlet to be reduced thereby.

19. In a charge forming device for internal combustion engines, walls forming an intake conduit, said intake conduit having an air inlet, a mixing chamber, and a discharge outlet, a fuel bowl for said charge forming device, means comprising a fuel supply conduit for maintaining the fuel level in said bowl, a main fuel passage leading from a point below the fuel level in said fuel bowl and having an outlet in the intake conduit, a throttle valve at a position in said intake conduit anterior to said fuel passage outlet, an air passage leading from an inlet at a point in said intake conduit slightly anterior to the closed position of said throttle to an outlet at said fuel passage, said air passage inlet being traversed by said throttle as it moves toward open position, and an air passage leading from a point in the intake conduit posterior to the throttle to a point above the fuel level in the fuel bowl, said air passage having its inlet located in position to be swept during the opening movement of the throttle so as to expose it to suction posterior to the throttle thereby.

20. In a charge forming device for internal

combustion engines, walls forming an intake conduit, said intake conduit having an air inlet, a mixing chamber, and a discharge outlet, a fuel bowl for said charge forming device, means comprising a fuel supply conduit for maintaining the fuel level in said bowl, a main fuel passage leading from a point below the fuel level in said fuel bowl and having an outlet in the intake conduit, a throttle valve at a position in said intake conduit anterior to said fuel passage outlet, an air passage leading from a point in said intake passage anterior to the closed position of said throttle to said fuel passage outlet, said throttle being of the butterfly type and being so arranged and positioned with respect to the air passage that the portion of the periphery of the valve nearest the opening of the air passage moves toward the air inlet of the intake conduit during the opening movement of the throttle, and in such proximity to the air passage opening as to permit suction posterior to the throttle to affect and reduce the pressure at the said air passage opening, and an air passage leading from a point in the intake conduit posterior to the throttle to a point above the fuel level in the fuel bowl.

21. In a charge forming device for internal combustion engines, walls forming an intake conduit, said intake conduit having an air inlet, a mixing chamber, and a discharge outlet, a fuel bowl for said charge forming device, means comprising a fuel supply conduit for maintaining the fuel level in said bowl, a main fuel passage leading from a point below the fuel level in said fuel bowl and having an outlet in the intake conduit, a throttle valve at a position in said intake conduit anterior to said fuel passage outlet, an air passage leading from a point in said intake conduit anterior to the closed position of said throttle to said fuel passage outlet, said throttle being of the butterfly type and being so arranged and positioned with respect to the air passage that the portion of the periphery of the valve nearest the opening of the air passage moves toward the air inlet of the intake conduit during the opening movement of the throttle, and in such proximity to the air passage opening as to permit suction posterior to the throttle to affect and reduce the pressure at the said air passage opening, and a second air passage leading from a point in said air passage anterior to the closed position of said throttle to said fuel passage outlet, said second air passage having an inlet in such proximity to said throttle valve when it is moved to fully open position as to cause the pressure at the said inlet to be reduced thereby, and an air passage leading from a point in the intake conduit posterior to the throttle to a point above the fuel level in the fuel bowl.

22. In a charge forming device for internal combustion engines, walls forming an intake conduit, said intake conduit having an air inlet, a mixing chamber, and a discharge outlet, a fuel bowl for said charge forming device, means comprising a fuel supply conduit for maintaining the fuel level in said bowl, a main fuel passage leading from a point below the fuel level in said fuel bowl and having an outlet in the intake conduit, a throttle valve at a position in said intake conduit anterior to said fuel passage outlet, an air passage leading from a point in said intake conduit anterior to the closed position of said throttle to said fuel passage outlet, said throttle being of the butterfly type and being so

arranged and positioned with respect to the air passage that the portion of the periphery of the valve nearest the opening of the air passage moves toward the air inlet of the intake conduit during the opening movement of the throttle, and in such proximity to the air passage opening as to permit suction posterior to the throttle to affect and reduce the pressure at the said air passage opening, and a branched passage having a connection to said intake conduit at a point posterior to the throttle, another connection to said intake conduit anterior to the throttle, and a third connection to the fuel bowl at a point above the fuel level therein.

23. In a charge forming device for internal combustion engines, walls forming an intake conduit, said intake conduit having an air inlet, a mixing chamber, and a discharge outlet, a fuel bowl for said charge forming device, means comprising a fuel supply conduit for maintaining the fuel level in said bowl, a main fuel passage leading from a point below the fuel level in said fuel bowl and having an outlet in the intake conduit, a throttle valve at a position in said intake conduit anterior to said fuel passage outlet, an air passage leading from a point in said intake conduit anterior to the closed position of said throttle to said fuel passage outlet, said throttle being of the butterfly type and being so arranged and positioned with respect to the air passage that the portion of the periphery of the valve nearest the opening of the air passage moves toward the air inlet of the intake conduit during the opening movement of the throttle, and in such proximity to the air passage opening as to permit suction posterior to the throttle to affect and reduce the pressure at the said air passage opening, and a second air passage leading from a point in said air passage anterior to the closed position of said throttle to said fuel passage outlet, said second air passage having an inlet in such proximity to said throttle valve when it is moved to fully open position as to cause the pressure at the said inlet to be reduced thereby, and a branched passage having a connection to said intake conduit at a point posterior to the throttle, another connection to said intake conduit anterior to the throttle, and a third connection to the fuel bowl at a point above the fuel level therein.

24. An anterior throttle carburetor comprising a mixing conduit, a venturi in said mixing conduit, a constant level fuel bowl, a main fuel passage leading from a point below the fuel level in said bowl and discharging into said venturi, a throttle valve anterior to the discharge outlet of said fuel passage, a suction passage leading from a point in said mixing conduit posterior to said throttle to a point in said constant level bowl above the fuel level, said suction passage having a branch leading to a point in the mixing conduit anterior to the throttle.

25. An anterior throttle carburetor comprising a mixing conduit, a venturi in said mixing conduit, a constant level fuel bowl, a main fuel passage leading from a point below the fuel level in said bowl and discharging into said venturi, a throttle valve anterior to the discharge outlet of said fuel passage, a suction passage leading from a point in said mixing conduit posterior to said throttle to a point in said constant level bowl above the fuel level, said suction passage having a branch leading to a point in the mixing conduit anterior to the throttle, and a branched air bleed passage connected to said fuel passage

and having one of its branches so positioned as to be swept by the edge of the throttle during its opening movement.

26. An anterior throttle carburetor comprising a mixing conduit, a venturi in said mixing conduit, a constant level fuel bowl, a main fuel passage leading from a point below the fuel level in said bowl and discharging into said venturi, a throttle valve anterior to the discharge outlet of said fuel passage, a suction passage leading from a point in said mixing conduit posterior to said throttle to a point in said constant level bowl above the fuel level, said suction passage having a branch leading to a point in the mixing conduit anterior to the throttle, and an air bleed passage connected to the fuel passage and having an inlet opening which is positioned anterior to the throttle when it is in closed position and is swept by the edge of the throttle as it moves toward open position.

27. In a carburetor, walls forming a mixing conduit, said mixing conduit having an air inlet, a mixing chamber, and a mixture outlet, a butterfly type throttle between said mixing chamber and said air inlet, a constant level fuel bowl a main fuel passage connected to said constant level bowl and discharging into said mixing conduit at a point posterior to said throttle, an air bleed passage having an inlet opening in said mixing conduit anterior to said throttle when it is in closed position, said opening being substantially spaced from the axis of said valve and located adjacent the edge which moves toward the inlet during its opening movement, and means controlled by the throttle for reducing the effect of said air bleed when the throttle approaches fully open position.

28. In a carburetor, walls forming a mixing conduit, said mixing conduit having an air inlet, a mixing chamber, and a mixture outlet, a butterfly type throttle between said mixing chamber and said air inlet, a constant level fuel bowl, a main fuel passage connected to said constant level bowl and discharging into said mixing conduit at a point posterior to said throttle, an air bleed passage having an inlet opening in said mixing conduit anterior to said throttle when it is in closed position, said opening being substantially spaced from the axis of said valve and located adjacent the edge which moves toward the inlet during its opening movement, and means controlled by the throttle for reducing the effect of said air bleed when the throttle approaches fully open position, said means comprising a branch passage having an inlet in said mixing conduit at a point anterior to the axis of said throttle, and having an extension which is approached by a part of the throttle as it moves toward open position.

29. In a carburetor, a mixture conduit, a throttle valve therein, a constant level fuel bowl, a main fuel passage connecting said bowl and said conduit posterior to said throttle valve, a bowl pressure control duct extending from the upper part of said bowl to said mixture conduit for controlling the fuel discharged from said passage, a connection between said conduit and a zone of atmospheric pressure, valve means controlling said duct and said connection and actuatable to open said conduit to said zone during starting and warm-up for increasing the pressure in the fuel discharge from said bowl into said conduit, said starting valve including portions 75 for reducing the effective size of the connection

13

between said bowl pressure control duct and said conduit, while increasing the effective size of the connection between said conduit and said zone of atmospheric pressure.
